UNITED STATES PATENT OFFICE.

HARRY S. BAUGHMAN, OF ALBION, MICHIGAN.

DRAFT-COLLAR FOR HORSES.

1,073,657.

Specification of Letters Patent. Patented Sept. 23, 1913.

Application filed March 11, 1910. Serial No. 548,576.

To all whom it may concern:

Be it known that I, HARRY S. BAUGHMAN, a citizen of the United States, residing at Albion, in the county of Calhoun and State 5 of Michigan, have invented certain new and useful Improvements in Draft-Collars for Horses, of which the following is a specification.

This invention relates to improvements in 10 draft collars.

My present improvements relate particularly to the class of draft collars shown in my application for Letters Patent filed June 9, 1909, Serial Number 501,205, and is, in 15 some respects, a modification and improvement thereof.

The main objects of this invention are: First, to provide an improved draft collar having shoulder members which may be 20 effectively adjusted to the shoulders of the animal and supported in their adjusted position. Second, to provide an improved draft collar which does not choke or chafe or produce undue pressure on the animal 25 wearing the same.

Further objects, and objects relating to structural details, will definitely appear from the detailed description to follow.

I accomplish the objects of my invention 30 by the devices and means described in the following specification.

The invention is clearly defined and pointed out in the claims.

A structure, which is a preferred embodiment of my invention, is clearly illustrated 35 in the accompanying drawing, forming a part of this specification, in which:

Figure 1 is a front elevation of my improved collar. Fig. 2 is a side view thereof. 40 Fig. 3 is a cross section of one side or element of the collar taken on a line corresponding to line z of Fig. 2. Fig. 4 is an enlarged detail vertical section, showing details of the connection for the hame to the 45 neck pad or saddle. Fig. 5 is a detail side elevation of the neck pad or saddle. Fig. 6 is a plan view of the neck pad or saddle members superimposed in the flat, or before they are conformed and joined.

50 In the drawings, similar reference characters refer to similar parts throughout the several views.

Referring to the drawings, the side members or hames A are of substantially the 55 same design as the hames of an ordinary harness, and I designate them herein as

hames. The hames illustrated are formed of wood having side plates 1 of metal. The hames A are adjustably connected at their upper ends by the strap 2 and at their lower 60 ends by the straps 3. The neck pad or saddle B is arranged between the hames and adjustably connected thereto by the pins 4 adapted to engage holes 5 transversely through the hames. See Fig. 4. These pins 65 are adapted to receive the cotter retaining pins 6.

The neck saddle, in the structure illustrated, is formed of two members of leather 7 and 8, the outer leather 7 being somewhat 70 longer transversely than the inner leather 8, the inner leather 8 being longer longitudinally of the saddle than the outer leather. In constructing the saddle, the eyelet pieces 75 9 are riveted to the inside of the side extensions of the outer member 7. The pins 4 project outwardly to engage the hame as described. The members 7 and 8 are sewed together as indicated by the dotted lines 10. This forms an effective connection for the 80 two members 7 and 8 and also an effective mounting for the pins 4. To adjust the collar to animals of different sizes, the pins are adjusted in different holes 5. The straps 85 2 are connected by the hames by the loops 12 which engage clips 11 adapted to receive the pins 4 so that the strap 2 is adjusted with the saddle.

The shoulder members or pads C are 90 formed of leather, or leather combined with other material not here illustrated. The forward ends of the shoulder members C are arranged over the neck plates 13, which are secured on the inner sides of the hames. These neck plates are conformed to the neck 95 as shown.

The shoulder members C extend rearwardly beyond the neck plates and their rear ends are supported by the supporting 100 arms D carried by the hames. The forward ends of the arms D are arranged in the angles of the L-shaped angle plates 16 which are attached to the rear sides of the hames, the angles facing outwardly and rearwardly, one arm of the angle being against the neck 105 plates 13 to assist in supporting the same. The clips 17 are clamped upon the arms by means of the bolts 18, so that a rigid connection is provided for the arms D to the hames.

110 The shoulder members C are provided with a rigid adjustable connection to their

supporting arms consisting, in the structure illustrated, of the plates 19 adapted to receive the adjusting screws 21, which are journaled in pairs of ears 20 on the inner 5 sides of the arms D. See Fig. 3. By means of this connection, the shoulder members C can be adjusted to fit them to the shoulders of the animals on which the collars are to be used, and they are retained in this adjusted position. The adjustment is also desirable to take up any slack or stretching of the shoulder members.

The traces, not here illustrated, are connected to the hames by the trace connections 15 which are independent of both the shoulder members C and their supporting arms D. This arrangement enables the complete adjustment of the shoulder members to the shoulders of the hames and to compensate 20 for any stretching which may result from use without any adjustment of the traces. The connection of the hames to the saddle permits the independent movement of the two side elements of the collar so that they 25 may move with the shoulders of the animal as the animal walks. This permits the shoulder members C to ride in continual contact with the shoulder, which is of very great advantage. The trace connection being independent of the shoulder members C 30 and their supporting arms D, the hitch of the traces does not materially affect the set of the collar and the collar may adjust itself to the pitch of the shoulders of the 35 particular animal without regard to the hitch,—that is, whether it is high or low.

My improved collar is very effective and is particularly adapted for use in heavy work, as there is no tendency to choke the 40 animal and it engages the horse's shoulders at the point where they are best adapted to sustain the load. Further, there is very little tendency to contract or compress the shoulders together. The structure is also 45 economical to produce and easily adjusted to animals having different shaped shoulders.

I have illustrated and described my improved collar in detail in a simple embodiment thereof. I have not attempted to illustrate or describe various modifications possible, as it is believed that the disclosures here made will enable those skilled in the art to adapt my improvements as conditions or taste will dictate. I desire, however, to be 50 understood as claiming my improvements specifically in the form illustrated, as well as broadly within the scope of the appended claims.

Having thus described my invention, what 60 I claim as new and desire to secure by Letters Patent is:

1. A horse collar comprising hames, neck plates secured thereto, shoulder members attached to said plates and extending rearwardly therefrom, rigid supporting arms

for said shoulder members carried by said hames and projecting rearwardly at the sides of said shoulder members, rigid adjustable connections for the outer ends of said shoulder members to their said supporting arms, and trace connections on said hames independent of said shoulder members and their said supporting arms. 70

2. In a horse collar, the combination of the hames, plates rigidly mounted on said hames, shoulder members arranged on and extending rearwardly from said plates, rigid supports for said shoulder members mounted on said hames and extending rearwardly therefrom at the sides of said shoulder members, and rigid adjustable connections for said shoulder members to said supports whereby said shoulder members may be conformed between said connections and said plates. 75

3. A horse collar comprising hames, shoulder members extending rearwardly therefrom, rigid shoulder member supporting arms carried by said hames and projecting rearwardly therefrom at the sides of the shoulder members, and a rigid adjustable connection for the outer ends of said shoulder members to their said supports whereby said shoulder members may be adjusted independently of the traces. 80

4. A horse collar comprising hames having neck plates thereon, shoulder members attached to the respective plates, rigid shoulder member supports connecting the hames and shoulder pad members, and adjustable rigid connections for the rear extremities of the shoulder pad members and their said supports at each side. 90

5. A horse collar comprising hames having neck plates thereon, shoulder members attached to said neck plates, rigid shoulder member supports connecting the hames and shoulder members, and an adjustable rigid connection between the shoulder members and their said supports. 105

6. A horse collar comprising neck members, shoulder members secured at their forward ends to the said neck members, supporting arms for said shoulder members, and rigid adjusting means for connecting said shoulder members to said supporting arms, comprising adjusting screws and coacting threaded members on said arms and shoulder members. 110

7. A horse collar comprising neck members, shoulder members secured at their forward ends to the said neck members, supporting arms for said shoulder members, and rigid adjusting means for connecting said shoulder members to said supporting arms. 120

8. In a horse collar, the combination of the hame, a neck plate attached thereto, a shoulder member attached to said plate and extending rearwardly therefrom, an angle plate fitted to said hame and bearing against 130

said neck plate, a rigid shoulder member support bearing against said angle plate, a clip fitted over the said shoulder member support, and bolts passing through said 5 hame, angle plate and clip.

9. In a horse collar, the combination with the hame and shoulder members, of a rear-wardly projecting shoulder member support having spaced ears on its inner side, a screw 10 journaled in said ears, and a block attached to the said shoulder member and threaded to engage said screw.

10. A horse collar comprising a hame, a shoulder member secured at its forward end to the said hame, a supporting arm for said shoulder member, and an adjusting means 15 for connecting said shoulder member to said supporting arm comprising an adjusting screw and coacting threaded members on said arm and shoulder member.
